UNITED STATES PATENT OFFICE.

ANKER S. LYHNE, OF BRIDGEPORT, CONNECTICUT.

SHADE-HOLDER

967,401.

Specification of Letters Patent. Patented Aug. 16, 1910.

Application filed February 18, 1909. Serial No. 478,570

To all whom it may concern:

Be it known that I, ANKER S. LYHNE, a citizen of the United States, residing at Bridgeport, county of Fairfield, State of Connecticut, have invented a new and useful Shade-Holder, of which the following is a specification.

This invention has for its object to provide a simple, inexpensive and ornamental shade holder that will hold a shade firmly and securely, may be easily operated to engage or disengage a shade and to engage and disengage a socket shell, which can be operated in either direction, shall be free from projecting parts and in which the gripping members shall be covered so that danger of injury to the hand of the operator shall be wholly avoided.

With these and other objects in view I have devised the novel shade holding device which I will now describe referring to the accompanying drawing forming a part of this specification and using reference characters to indicate the several parts:

25 Figure 1 is an elevation of my novel shade holder as in use, a shade being shown as gripped thereby and as attached to a socket shell; Fig. 2 a partial vertical section on an enlarged scale showing the locking devices in the releasing position; Fig. 3 a similar view showing the parts in the locking position, the section line being indicated by 3—3 in Fig. 4; Fig. 4 a section on the line 4—4 in Figs. 2 and 3 looking in the direction of the arrow, the spring clamping ring being shown in full lines in the locking position and in dotted lines in the releasing position; Fig. 5 a section on the line 5—5 in Fig. 2 looking in the direction of the arrow; and Fig. 6 is a section on the line 6—6 in Fig. 3 looking in the direction of the arrow.

10 denotes a shade provided at its upper end with the usual flange 11 and below the flange with a groove 12, and 13 a socket shell having near its lower end the usual external rib 14.

15 denotes the body or shade securing member of my novel shade holder which may be made of any preferred ornamental configuration preferably substantially as shown in the drawing. At the lower end of the body is a vertical flange 16 which is provided with a circumferential rib 36, the inner side of which comprises a groove 17 to receive an outwardly acting spring clamp-

ing ring 18. The clamping ring is provided with a plurality of outwardly extending bosses or bends 19, in the present instance three, and the flange is provided with a corresponding number of slots or openings 20 which receive the bosses or bends (see Fig. 4).

21 denotes a locking sleeve which incloses the flange on the body, oscillates freely thereon and is retained in position by closing in the edges of the sleeve as at 22 and 23 (see Figs. 2 and 3). The sleeve is provided with a rib 24 (knurled for convenience in operation), the inner side of which comprises a groove 25 to receive rib 36 on the flange and is also provided with slots or openings 26 adapted to register with slots or openings 20 in the flange. 65 70

The operation in locking or releasing a shade will be readily understood from Figs. 2, 3 and 4. The locking and releasing is effected by oscillation of the locking sleeve in either direction. When slots 29 in the flange and slots 26 in the locking sleeve are in alinement bosses or bends 19 on the clamping ring will spring outward into said alined slots and the clamping ring will lie in groove 17 in the flange (see Fig. 2 and dotted position in Fig. 4). In this position of the clamping ring, the flange of a shade may be passed upward within flange 16 of the holder or removed therefrom. When the locking sleeve is oscillated the rear end walls of the slots in the sleeve will co-act with the front end walls of the slots in the flange (either end of said slots may be the front or rear end depending of course upon the direction of movement of the sleeve) and will engage and force the bends of the clamping ring inward and will move said ring from the releasing position shown in dotted lines in Fig. 4 to the locking position shown in full lines. The clamping ring remains relatively stationary.

100 relatively stationary in use; that is, it has no oscillatory movement and is wholly covered in the locking position. It is of course an open ring, the ends being left separated far enough to permit the locking movement. In the locking position the portions of the ring intermediate the bosses are forced under the flange of the shade and into the groove 12, thereby locking the shade firmly in the holder. Further forward movement of the sleeve, or backward movement thereof, will place the slots or openings in the sleeve in alignment with the slots or openings in the 105 110

flange of the body and the resiliency of the ring will cause the bosses or bends to spring outward into the alined slots, the ring moving from the locking position shown in full lines in Fig. 4 to the releasing position shown in dotted lines and leaving the shade wholly free.

The locking of the holder to a socket shell is effected in a somewhat similar manner. 10 At the upper end of body 15 is a vertical flange 27 which is provided with an internal groove 28, and with a plurality of slots or openings 29, in the present instance three. 30 denotes an outwardly - acting spring 15 locking sleeve which lies on the inner side of flange 27 and oscillates freely thereon. At the lower end of the sleeve is a flange 31 which is turned outward to engage the body and at the upper end is an outwardly curved 20 roll 32 knurled for convenience in operation. This roll engages the upper end of flange 27 and the roll and flange 31 retain the sleeve against detachment. The sleeve is provided with a plurality of outwardly curved locking 25 lugs or bosses 33 corresponding in number with slots or openings 29 in the flange and registering with groove 28 and the slots. The inner sides of these lugs or bosses comprise grooves 35. The locking sleeve is of 30 course a divided sleeve and in order to retain the ends thereof firmly in place, I preferably provide at the ends outwardly extending lugs or bosses 34 which engage groove 28 in flange 27 in the same manner as locking 35 lugs 33.

The operation of engaging or disengaging a socket shell is practically the same as engaging or disengaging a shade. When locking lugs 33 are in alinement with slots 29, 40 the resiliency of the sleeve will force the lugs outward into the slots and will permit the sleeve to expand. In this position of the sleeve, it may be passed over the lower end of a socket shell, the rib 14 thereon slipping 45 into alinement with the groove 28 in flange 27 and the grooves 35 in the inner faces of the locking lugs. Rotation of the locking sleeve in either direction will cause the forward ends of the locking lugs (either end 50 may be the forward end depending on the direction of movement) to engage the inner wall of groove 28 in flange 27 and be forced inward thereby, the inner walls of grooves 35 in the locking lugs being forced into close 55 engagement with rib 14 on the socket shell and locking the holder securely thereto. Further forward movement of the locking sleeve, or backward movement thereof, will again place the locking lugs in alinement 60 with slots 29 in the flange into which the locking lugs will spring through the resiliency of the sleeve thereby relieving the grip of the locking lugs on rib 14 and releasing the holder from the socket shell so that it 65 may be readily removed. It should be

noted that when the locking lugs are in the releasing position end lugs 34 remain in engagement with groove 28, thereby holding the ends of the sleeve securely in place. These end lugs, however, do not interfere with attachment to or detachment from a socket shell when the locking lugs are in the releasing position. Locking sleeves 21 and 30 both serve an additional purpose in that they greatly strengthen the holder and make it rigid at the points where all the strain of use is applied.

Having thus described my invention, I claim:

1. A shade holder comprising a receiving member having slots, spring means having bosses engaging said slots and an oscillating locking sleeve engaging the receiving member and having slots adapted to aline with the slots in said member in the unlocking position, said sleeve when oscillated forcing said spring means to the locking position.

2. A shade holder comprising a receiving member having an internal groove and slots, spring means adapted to enter the groove in the unlocking position and having bosses engaging the slots, and an external locking sleeve having slots adapted to receive the bosses in the unlocking position, oscillation of the sleeve acting to force said spring means to the locking position.

3. A shade holder comprising a flange having an external rib and internal groove and slots, spring means lying in said groove and having bosses engaging the slots and a locking sleeve adapted to oscillate on the flange and having a groove which receives the rib and slots adapted to aline with the slots in the flange, said bosses being engaged and said spring means forced inward by oscillation on the locking sleeve, substantially as described, for the purpose specified.

4. A shade holder comprising a body adapted to receive a shade and having an internal circumferential groove and slots, an outwardly expanding clamping ring having bosses engaging the slots, and ring being adapted to lie in the groove in the unlocking position and to engage a shade in the locking position and a locking sleeve having slots adapted to aline with the slots in the body in the unlocking position, oscillation of said sleeve forcing the ring to the locking position.

5. A shade holder comprising a body adapted to engage a shade and having an internal circumferential groove and slots in line with said groove, an outwardly expanding clamping ring loosely supported in the groove and having bosses engaging the slots, and a locking sleeve having slots in line with the slots in the body, so that when the slots in the sleeve and body are in vertical alinement the ring will expand outward and

when the sleeve is oscillated the bosses will be engaged and the ring forced inward to the locking position.

6. A shade holder comprising a body having at its lower end a flange with an external rib and internal groove and slots, a spring clamping ring lying in said groove and having bosses lying in the slots and a locking sleeve adapted to oscillate on the flange and having a groove which receives the rib on the flange and slots adapted to aline with the slots in the flange, the bosses on the clamping ring being forced inward by the end walls of the grooves in the sleeve and body when the sleeve is rotated, whereby the ring is forced to the locking position, and said bosses springing through the slots in the sleeve when said slots are in alinement

with the slots in the flange, which leaves the ring in the releasing position.

7. A shade holder having means for connecting it to a socket and comprising a receiving member having slots, a spring clamping ring having bosses engaging said slots and an oscillating locking sleeve engaging the receiving member and having slots adapted to aline with the slots in said member in the unlocking position, said sleeve when oscillated forcing the ring inward to the locking position.

In testimony whereof I affix my signature, in presence of two witnesses.

ANKER S. LYHNE.
